UNITED STATES PATENT OFFICE.

FREDERICK W. HOLDERLE AND CARL L. HOLDERLE, OF ROCHESTER, NEW YORK.

DESIGN FOR A BEVERAGE-DISPENSER.

59,652.

Specification for Design.

Patented Nov. 15, 1921.

Application filed June 18, 1921. Serial No. 478,755. Term of patent 7 years.

To all whom it may concern:

Be it known that we, FREDERICK W. HOLDERLE and CARL L. HOLDERLE, citizens of the United States, residing at Rochester, in the county of Monroe and State of New York, have invented a new, original, and ornamental Design for a Beverage-Dispenser, of which the following is a specification, reference being had to the accompanying drawing, forming part thereof.

The figure is a perspective view of the beverage dispenser, showing our new design.

We claim:

The ornamental design for a beverage dispenser, substantially as shown.

FREDERICK W. HOLDERLE.
CARL L. HOLDERLE.
